UNITED STATES PATENT OFFICE.

ALFRED H. WILLETT, OF WEST NEW YORK, NEW JERSEY, ASSIGNOR TO AMERICAN ARCH COMPANY, OF NEW YORK, N. Y., A CORPORATION OF DELAWARE.

FIRE-BRICK ARCH.

Application filed December 4, 1918. Serial No. 265,191.

To all whom it may concern:

Be it known that I, ALFRED H. WILLETT, a citizen of the United States, residing at West New York, in the county of Hudson 5 and State of New Jersey, have invented certain new and useful Improvements in Fire-Brick Arches, of which the following is a specification.

This invention has reference to an im- 10 proved form of fire brick arch such as is used in fire boxes of locomotives, and to a novel construction of fire brick for use in such structures.

The invention is designed primarily for 15 use in fire boxes where there are supporting circulating tubes for the bricks which are spaced such a distance apart and so placed with respect to the fire that it is desirable to use a double row of bricks between adja- 20 cent tubes placed at an incline with the horizontal plane and leaning against each other at the upper ends to provide support for the contacting units.

One of the objects of this invention is the 25 provision of a brick for this character of an arch which will be invertible and which will rest securely upon the supporting tube either side up and have a suitable bearing against its oppositely disposed or complementary 30 brick with interengaging or interlocking means that will fit in either position.

Another object of this invention is the 35 provision of a brick of this invertible type which has a cut-away or recessed portion so disposed that when a number of them are 40 assembled in an arch and adjacent bricks placed in different positions an aperture will be formed through the arch, while if placed in the same position, the arch will be closed or imperforate.

The above, as well as such other objects as may hereinafter appear, I attain by means of a construction which I have illustrated in preferred form in the accompanying 45 drawings, wherein:—

Figure 1 is a horizontal sectional view of a fire box showing the upper side of an arch embodying my invention; Figure 2 is a longitudinal sectional view taken on the line 50 II—II of Fig. 1; Figure 3 is a transverse sectional view through a fire box; Figure 4 is a section through one of the bricks showing the cut-away or recessed portion; and Figure 5 is an end view of one of the mid-

dle bricks used in the arch shown in Figures 55 1 and 3.

The fire box construction which I have 60 illustrated comprises a flue sheet 1, a crown sheet 2, an inner back sheet 3, and a water leg 4, all of usual construction, and connect- 65 ing the water leg 4 with the water space 5 I provide two brick supporting circulation tubes 6 which, as indicated in Fig. 1, are spaced a considerable distance apart, there 70 being wing bricks 7 provided between the supporting tubes 6 and the side sheets 8 which wing bricks may be of any preferred construction suitable to the requirements and the size of the arch.

Referring now more particularly to Fig. 70 3, it will be seen that between the two arch tubes 6, I arrange a series of pairs of bricks 9 which are provided with curved surfaces 75 at 10 resting against the tubes 6 formed so that they will provide a suitable support 75 whichever face of the bricks is placed upward.

The bricks 9 are sloped upwardly from 80 the horizontal plane connecting the tubes 6 and rest against each other at the center 85 and each of the bricks is provided with a pair of angular supporting faces 11 each face having a projecting rib 12 and a complementary recess 13, shown most clearly in Fig. 5, these ribs or projections and recesses 85 being so disposed that those on one face are interengaged with the companion brick whichever face of the brick 9 is placed uppermost.

The sides of the bricks 9 have cut-away 90 parts or recesses 14 which extend more than half way through the thickness of the brick, as a result of which the recesses 14 will provide apertures through the arch if the 95 bricks are placed with each adjacent pair alternating in position, as indicated in Figs. 1 and 2, while the arch will not have apertures if adjacent bricks are placed with the recesses all looking in the same direction as is the case with the first three pairs of 100 bricks shown at the right of Fig. 1. The bricks 9 are preferably made thicker through their upper ends than at the end which rests upon the tubes as I secure there- 105 by a broader contacting face 11 and greater strength for the central part of the arch.

I claim:—

1. A tube supported fire brick arch con-

struction comprising a series of pairs of invertible bricks supported between two tubes, said bricks in each pair being inclined toward and resting against each other and 5 each brick having at the meeting end two oppositely inclined supporting surfaces constructed to permit the bricks to be rested against each other either face upward.

2. A fire brick arch structure comprising 10 in combination a pair of brick supporting tubes and a series of pairs of bricks supported upon said tubes inclined toward and resting against each other with supporting faces constructed so that the bricks may be 15 rested against each other either face upward, and recesses in said bricks so disposed as to provide apertures through the arch when alternate bricks are placed in inverted position and to form an imperforate arch 20 when the bricks are placed in the same position.

3. An invertible brick for fire box arch constructions in which two bricks are adapted to lean against each other in arched relation, having a support engaging surface at 25 one end and two brick engaging surfaces at the other end, one of which brick engaging surfaces is utilized in one position of the brick and the other in the other position, 30 said support engaging surface being adapted to cooperate with either of the two brick engaging surfaces.

4. An invertible fire brick for arch constructions adapted to lean against an adjacent brick in arched relation and having 35 means at one end for supporting it upon an arch tube and provided at the other end with two oppositely inclined faces so constructed that the brick may be leaned against another brick either side up.

5. An invertible fire brick for arch constructions adapted to lean against an adjacent brick and having means at one end for supporting it upon an arch tube and provided at the other end with two oppositely inclined faces so constructed that it may be 45 leaned against another brick either side up, said faces having interlocking means for engaging a companion brick when in contact therewith.

6. A fire brick for arch constructions adapted to lean against an adjacent brick

and having means for supporting it upon an arch tube and provided with faces opposite its tube supported end so constructed 55 that it may be placed either side up, said brick having a recess formation whereby when a number are assembled to form an arch and alternate bricks are placed in inverted position, apertures will be formed 60 through the arch but if all the bricks are placed in the same position a closed arch will be formed.

7. An invertible fire brick for arch constructions adapted to lean against an adjacent 65 brick and having means at one end for supporting it upon an arch tube and provided at the other end with two oppositely inclined faces so constructed that the brick may be leaned against another brick either 70 side up, and tongue and groove formations constructed to interengage with a companion brick when placed in contact therewith.

8. A fire brick arch structure comprising 75 in combination a series of pairs of bricks the bricks in each pair being inclined toward and resting against each other with their inner ends constructed so that the bricks may be rested against each other with either face upward, and recesses in said 80 bricks so disposed as to provide apertures through the arch when alternate bricks are placed in inverted position and to form an imperforate arch when the bricks are placed in the same position.

9. An invertible brick for fire box arch constructions having a support engaging surface at one end; two brick engaging surfaces at the other end, one of which brick engaging surfaces is utilized in one position 90 of the brick and the other in the other position, said support engaging surface being adapted to cooperate with either of the two brick engaging surfaces; and a recess formation whereby, when a number of such 95 bricks are assembled to form an arch and alternate bricks are placed in inverted position, apertures will be formed through the arch, but whereby, if all of such bricks in an arch construction are placed in the same 100 position, a closed arch will be formed.

In testimony whereof, I have hereunto signed my name.

ALFRED H. WILLETT.
